Patented Mar. 20, 1923.

UNITED STATES PATENT OFFICE.

LOUIS E. MURPHY, OF PHILADELPHIA, PENNSYLVANIA, ASSIGNOR TO E. E. HOUGHTON & COMPANY, OF PHILADELPHIA, PENNSYLVANIA, A CORPORATION OF PENNSYLVANIA.

TEXTILE-SCOURING OIL.

No Drawing. Application filed August 14, 1918. Serial No. 249,889.

To all whom it may concern:

Be it known that I, LOUIS E. MURPHY, a citizen of the United States, residing in Philadelphia, Pennsylvania, have invented 5 certain Improvements in Textile-Scouring Oils, of which the following is a specification.

My invention relates to the art of scouring, cleansing and finishing textile fabrics; 10 and the object of my invention is to provide an improved oleaginous, liquid detergent, particularly available for use in the scouring, fulling and finishing of woolen and worsted raw stock, yarns, woolen or worsted 15 piece goods, as well as similar material having an admixture of cotton.

The improved product constituting my invention is designed to take the place of the "soap" and alkali heretofore employed for 20 the operations noted above, and in addition to effecting the desired result in a better manner than the various products heretofore employed for the same or similar purposes, it is materially cheaper on the one hand and 25 requires less material for a given amount of work on the other hand.

When used with alkali in proper proportions, it replaces the "soap" for the purposes mentioned above and with better results in 30 the finished product; that is to say, its use produces cleaner stock and goods, with material economy in cost.

In preparing my improved product, I first sulfonate what is known as ordinary commercial castor oil; the finished product showing approximately 23% acid, and being what is known as a 70% strength oil; that is to say, 70% oil, and 30% aqueous moisture.

I then sulfonate ordinary maize or corn 40 oil; the finished product showing a strength of approximately 80% oil and 20% water.

I then prepare a neutral saponaceous detergent of the consistency of soft soap; the materials employed being as follows, in substantially the proportions named:

Olive oil	36	gals.
Extra prime lard oil	216	gals.
Corn (or maize) oil	36.5	gals.
Cocoanut oil	15.5	gals.
Neat's foot oil	15.5	gals.
Water	1,124	gals.
Caustic potash	314	lbs.
Caustic soda	183	lbs.

When this operation is complete I take 55 approximately 12% of the sulfonated 70% castor oil (23% acid); add approximately 8.16% of the sulfonated corn oil; approximately 6.48% of the neutral saponaceous detergent, and approximately 4.81% of what 60 is known as a bloomless neutral hydrocarbon lemon-colored oil.

After this approximately 14.76% of water is stirred in and the whole mass agitated 65 thoroughly for about thirty minutes.

I then add approximately 1.81% of a caustic soda solution of 60° Twaddle, and agitate the mass for a short time.

I then add approximately 29% of what is commercially known as 98% oleic acid, with 70 a further addition of approximately 14% water and agitate.

After this mass has been agitated for fifteen (15) or twenty (20) minutes, I add approximately 9% of a caustic soda solution of 75 60° Twaddle and approximately 3 ounces of formaldehyde to prevent fermentation.

The temperature at which the desired mixture is effected may be approximately 150° F., and the resulting product is alkaline. 80

The sulfonated oil used could be composed wholly of the castor oil, but maize (or corn) oil has been used in order to reduce the cost of the finished material.

In this combination the use of the sulfonated oil furnishes softening properties; the neutral saponaceous detergent cleansing properties; the neutral hydrocarbon oil penetrating and emollient properties; and the alkali used furnishes part of the scouring properties.

The finished oil when used in combination with alkali like caustic soda or soda ash produces a scouring, fulling and finishing oil superior in every way to the "soaps" 95 heretofore in general use.

As an example of its efficiency and adaptability over the usual "soap" in the scouring bath for use upon such goods as "tricotines", "gabardines", "panama cloth", 100 "ottoman cloth", "serges", "fancy goods", etc., where 50 gallons of water, 40 lbs. of soap and 12 lbs. of soda ash were formerly necessary to obtain the desired results, I have secured the same effect with 50 gallons of water, 18 lbs. of my improved textile scouring oil, and 14 lbs. of soda ash. 105

In the scouring of domestic wool, I have

replaced a 400-gallon bath formerly used, which included 200 lbs. of soap, 20 lbs. of caustic soda and 85 lbs. of soda ash, with 100 lbs. of my improved textile scouring oil, 25 lbs. caustic soda and 62 lbs. of soda ash.

Where the soap heretofore employed was desired for some particular purposes, for instance in the scouring and fulling of 16-oz. 10 khaki cloth, where 110 gallons of water, 110 lbs. of soap and 30 lbs. of soda ash were used, I have replaced the same with 110 gallons of water, 25 lbs. of soap, 25 lbs. of my improved textile scouring oil and 30 lbs. of 15 soda.

While I have described with some particularity certain proportions of materials employed, I do not wish to be limited to the exact proportions named.

20 I claim:

1. As a new article of manufacture, a textile scouring oil comprising an oleaginous liquid body containing sulfonated castor oil, and sulfonated maize (or corn) oil, homogeneously combined with a neutral saponaceous detergent resulting from the combination of olive oil foots, lard oil, corn oil, cocoanut oil, neat's foot oil, an alkali hydrate, and water.

2. A textile scouring oil comprising a body of sulfonated vegetable oil homogeneously combined with a neutral saponaceous detergent resulting from the combination of olive oil foots, lard oil, corn or maize oil, cocoanut oil, neat's foot oil, water, and an alkaline hydrate.

3. As a new article of manufacture, a textile scouring oil comprising an oleaginous liquid body containing sulfonated castor oil

with an acid reaction, sulfonated maize (or 40 corn) oil, and a saponaceous detergent resulting from the combination of olive oil foots, lard oil, corn oil, cocoanut oil, neat's foot oil, alkaline hydrate, and water; the hydrate being present in sufficient quantity 45 to render the finished product alkaline.

4. As a new article of manufacture, a textile scouring oil comprising an oleaginous liquid body containing approximately 12% of a 70% sulfonated castor oil; approximately 8.16% of a sulfonated corn oil; approximately 6.48% of a neutral saponaceous detergent; approximately 4.81% of a bloomless neutral hydrocarbon lemon-colored oil; approximately 14.76% of water; approximately 1.81% of caustic soda solution of 60° Twaddle, and approximately 29% of oleic acid, and approximately 14% additional water, and approximately 9% caustic soda solution of 60° Twaddle.

5. As a new article of manufacture, a textile scouring oil comprising an oleaginous liquid body containing approximately 12% of sulfonated castor oil (23% acid); approximately 8.16% of a sulfonated corn oil; 65 approximately 6.48% of a neutral saponaceous detergent resulting from the combination of vegetable oils, animal oils, an alkaline body, and water; approximately 4.81% of a bloomless neutral hydrocarbon 70 lemon-colored oil; approximately 14.76% of water, with approximately 1.81% of caustic soda solution of 60° Twaddle; approximately 29% of oleic acid; approximately 14% additional water, and approximately 9% of caustic soda solution of 60° Twaddle.

LOUIS E. MURPHY.
